Filed June 10, 1964, Ser. No. 80,343

Term of patent 14 years

(Cl. D71—1)

FIG. 8.

FIGURE 1 is a front plan view of a first embodiment of a propeller bracket embodying my new design;

FIGURE 2 is a typical right or left side elevational view thereof;

FIGURE 3 is a rear elevational view thereof;

FIGURE 4 is a typical top or bottom elevational view thereof;

FIGURE 5 is a front plan view of a second embodiment of a propeller bracket embodying my new design;

FIGURE 6 is a rear elevational view thereof;

FIGURE 7 is a typical top or bottom elevational view thereof;

FIGURE 8 is a typical right or left side elevational view thereof.

The dominant features of my design reside in the portions shown in full lines. The propeller shown in broken lines in FIGURES 5, 6, 7, and 8 is included for illustrative purposes only.

I claim:

The ornamental design for a propeller bracket, substantially as shown and described.
